*Primary Examiner—Susan J. Lucas
Assistant Examiner—Jennifer Rivard***[57] CLAIM**

The ornamental design for a cigar, as shown and described.

DESCRIPTION

FIG. 1 is a perspective view of the first embodiment of a cigar according to my design;

FIG. 2 is a rear-end elevational view of the cigar of FIG. 1;

FIG. 3 is a front-end elevational view of the cigar of FIG. 1;

FIG. 4 is a left side elevational view of the cigar of FIG. 1 (the opposite side elevational view of the cigar of FIG. 1 is a mirror image of this left side);

FIG. 5 is a top plan view of the cigar of FIG. 1 (the bottom plan view of the cigar of FIG. 1 is a mirror image of this top plan view);

FIG. 6 is a perspective view of the second embodiment of a cigar according to my design;

FIG. 7 is a rear-end elevational view of the cigar of FIG. 6; FIG. 8 is a front-end elevational view of the cigar of FIG. 6; FIG. 9 is a left side elevational view of the cigar of FIG. 6 (the opposite side elevational view of the cigar of FIG. 6 is a mirror image of this left side);

FIG. 10 is top plan view of the cigar of FIG. 6;

FIG. 11 is a bottom plan view of the cigar of FIG. 6;

FIG. 12 is a perspective view of the third embodiment of a cigar according to my new design;

FIG. 13 is a rear-end elevational view of the cigar of FIG. 12;

FIG. 14 is a front-end elevational view of the cigar of FIG. 12;

FIG. 15 is a left side elevational view of the cigar of FIG. 12 (the opposite side elevational and top and bottom plan views of the cigar of FIG. 12 are mirror images of this left side);

FIG. 16 is a perspective view of the fourth embodiment of a cigar according to my design;

FIG. 17 is a rear-end elevational view of the cigar of FIG. 16;

FIG. 18 is a front-end elevational view of the cigar of FIG. 16;

FIG. 19 is a left side elevational view of the cigar of FIG. 16 (the opposite side elevational view of the cigar of FIG. 16 is a mirror image of this left side);

FIG. 20 is a top plan view of the cigar of FIG. 16;

FIG. 21 is a bottom plan view of the cigar of FIG. 16;

FIG. 22 is a perspective view of the fifth embodiment of a cigar according to my design;

FIG. 23 is a rear-end elevational view of the cigar of FIG. 22;

FIG. 24 is a front-end elevational view of the cigar of FIG. 22;

FIG. 25 is a left side elevational view of the cigar of FIG. 22 (the opposite side elevational view of the cigar of FIG. 22 is a mirror image of this left side); and,

FIG. 26 is a top plan view of the cigar of FIG. 22 (the bottom plan view of the cigar of FIG. 22 is a mirror image of this top plan view).
